Primary Examiner—Gary D. Watson*Attorney, Agent, or Firm*—Evenson, McKeown Edwards & Lenahan P.L.L.C**[57] CLAIM**

The ornamental design for a front face of a wheel cover, as shown and described.

DESCRIPTION

FIG. 1 is a front view of a front face of a wheel cover according to my novel design; and,

FIG. 2 is a front perspective view of a front face of a wheel cover according to my novel design wherein the broken lines are for illustrative purposes only and form no part of the claimed design.
